MEMORANDUM DEVICE COMBINED WITH
MEANS FOR MOUNTING LAMELLAR ARTI-
CLES

Mathias Dirsch, Hamburg, Germany

Application May 19, 1938, Serial No. 208,881. Re-
newed April 13, 1940. In Germany May 29,
1937

2 Claims. (Cl. 40—18)

The object of the present invention is to provide an improved article of manufacture comprising a memorandum device combined with means for mounting lamellar articles such as photographic prints, printed labels and the like.

Known combined memorandum sheets and means for sticking photographic prints in albums consist of a fastening strip to be secured to the rear of a photographic print and a memorandum sheet guided by said strip and provided with a grip. In this construction both sides of the fastening strip are provided with an adhesive so that the strip may be stuck respectively to the photographic print on the one hand and to the album on the other hand. An extension of the memorandum sheet is guided by the fastening strip. The memorandum sheet is usually hidden behind the photographic print, whereby only its grip projects. However, if the person inspecting the album wishes to have further details about the print, the memorandum sheet may be pulled out by means of the grip.

In order to prevent, when pushing back the memorandum sheet, the corners thereof from striking against the lower edge of the print, it has been suggested to have an angle of less than 90° between the memorandum sheet and its extension. This was supposed to ensure when the memorandum sheet is pulled out, that the upper edges thereof remain beneath the edge of the photographic print. This arrangement is, however, not always successful since, when the memorandum sheet has been inaccurately secured in the album, the upper corners thereof may also be released by or come clear of the print. This arrangement, further, has the drawback that upon sticking-in the fastening strip the protruding upper corners may lie between this strip and the picture or the leaf of the album so causing the memorandum sheet to be stuck fast and preventing it being pulled out. Finally, upon pushing-back the memorandum sheet the upper corners thereof always strike against the fastening strip and in this way may gradually destroy the adhesion or fixture of the picture.

A further object of the present invention is to avoid the drawbacks enumerated above.

In the known constructions, moreover, a rectangular slit, that is a slit with parallel sides, of the extension of the memorandum sheet engages with the fastening strip.

A still further object of the present invention is so to construct the slit that when the memorandum sheet is pushed back, the slit bears close-

ly against the fastening strip and the memorandum sheet is thus prevented from sliding forward by itself. Vice versa, the pulling-out of the memorandum sheet is facilitated since in this movement the fastening strip moves towards the widened part of the slit.

Yet a further object of the present invention is to provide the memorandum sheet with a grip, the two sides of which are of a color corresponding to the light and dark colours respectively as usually employed for photographic albums and the like, whereby the same memorandum sheet may be used for albums of different colours.

A constructional form of the invention is illustrated by way of example in the accompanying drawings, wherein:

Fig. 1 shows a leaf of an album for photographic prints with a photograph stuck thereon, Fig. 2 shows a side elevation, and

Fig. 3 shows a cross section taken on line III—III of Fig. 1.

Fig. 4 is a view of an adhesive strip used herein showing one face or side thereof;

Fig. 5 is an edge view of such a strip;

Fig. 6 is a view similar to Fig. 4 but showing the opposite face or side of the strip;

Fig. 7 is a face view showing one side of a memorandum sheet used herewith;

Fig. 8 is a view similar to Fig. 7 but showing the opposite side of the strip;

Fig. 9 is an enlarged face view of the strip and sheet in assembled relation;

Fig. 10 is a section on the line X—X of Fig. 9.

The thicknesses of the leaves, sheet and so on in the drawings have been considerably exaggerated in order to render it clearer.

A print *b* is secured to a leaf *a* of an album for photographic prints. This is effected by a strip *d*, *e*, *f*, provided on both sides with an adhesive and folded in the manner illustrated, the center portion *d* of which is stuck to the print and its ends *f* being stuck on the one side to the leaf *a* of the album and on the other side to the print.

It will be seen from Figs. 4, 5 and 6 that the center portion *d* is flat and on one side is provided with an adhesive coating as shown in Fig. 4, while its other or inner side is free from adhesive as shown at *d'* in Fig. 6. The portions *f* extend outwardly beyond the ends of the portion *d* and extend inwardly of the ends of the portion *d* to form a slot *e*. The inner ends of the portions *f* are connected to the ends of the portion *d* by portions *m*, the strip when thus folded providing a T-shaped central part formed of a flat loop connected to the base members *f* by a short stem. 55

The interior of the loop is free from adhesive. The portions *f* on the loop provided side of the strip are provided with adhesive which terminates free of the loop as at *o* while on its other side the portions *f* are provided at their ends with adhesive which terminates in spaced relation to the slot *e* as at *p*. The portions between the loop and members *f* are also thus free from adhesive.

10 In this connection it is to be presumed that in Fig. 3 of the drawings one side of the ends *f* of the strip should bear against the leaf *a* of the album and the other side against the rear of the print, this being clear from the enlarged view shown. Obviously, the device can be turned over so that the center portion *d* could just as well be stuck to the leaf *a* of the album and the parts *f* bear against the print *b*. A sheet *g* for notes having an upper extension *h* is slidably arranged 15 upon the strip *d, e, f*. And slot *i* provided in this extension embraces, and is guided by the central bridge *e* of the strip *d, e, f*. The full lines in Fig. 1 show the memorandum sheet pulled out whereas the dot and dash lines show it pushed 20 back beneath and behind the print. The memorandum sheet is intended to receive any notes relative to the respective print. The pulling out or pushing back movement is effected by means 25 of a grip *k* which is the only part projecting from 30 below the print when the sheet is pushed home.

In order to facilitate the pushing back movement of the memorandum sheet *g* and to prevent the fastening strip *d, e, f* from becoming damaged, the upper edge of the sheet is constructed 35 in such a manner that the angle α between it and its extension *h* is greater than 90° , see Fig. 1.

The slit *i* in the extension *h* is reduced in 40 wedge-like manner from top to bottom, that is in the direction of the memorandum sheet. When the memorandum sheet is pulled out, the bridge *e* of the fastening strip *d, e, f*, is then 45 situated in the wider portion of the slit, so that the memorandum sheet may be easily displaced. On the other hand, when the memorandum sheet is pushed home the bridge *e* is situated in the narrower portion of the slit so that the memorandum sheet is securely held in position.

The grip *k* is integral with the memorandum sheet *g* and preferably dark on one side and light 50 on the other side. It may therefore be used for albums with dark and light leaves since the strip *d, e, f*, permits of having uppermost one or other side of the memorandum sheet and the grip.

55 In the example hereinbefore described with reference to the accompanying drawings, the article to be mounted has been referred to as

a photographic print and the background on which it is mounted has been referred to as a leaf of an album. It will be apparent that the invention is not restricted to this particular case but is generally applicable to the mounting of 5 lamellar articles.

I claim:

1. A mount for sheet-like articles such as photographs and the like including a memorandum sheet and a mounting strip therefor, 10 said sheet having a substantially rectangular body, a grip tab projecting centrally from one of the longer edges of the body, a relatively narrow extension forming a tongue projecting at right angles from the opposite edge and having 15 a longitudinal slot therein, the upper edge of said body being inclined away from said extension on both sides thereof, said mounting strip comprising a single strip of foldable material folded to provide a central flat loop portion and 20 ends forming a base connected to the loop by a short stem, said stem extending through the slot of the sheet with the head on one side of the tongue and the base portions projecting outwardly from the edges of the tongue, said base portions 25 having adhesive on the side remote from the tongue, the other side of said base portions and the side of the loop remote from the tongue being also provided with adhesive, the portions of the strip engaging the tongue being free from 30 adhesive.

2. A mount for sheet-like articles such as photographs and the like including a memorandum sheet and a mounting strip therefor, said sheet having a substantially rectangular body, a 35 grip tab projecting centrally from one of the longer edges of the body, a relatively narrow extension forming a tongue projecting at right angles from the opposite edge and having a longitudinal slot therein, the upper edge of said body being inclined away from said extension on both sides thereof, said mounting strip comprising a single strip of foldable material folded to provide a central flat loop portion and ends forming a base connected to the loop by a short stem, 40 said stem extending through the slot of the sheet with the head on one side of the tongue and the base portions projecting outwardly from the edges of the tongue, said base portions having adhesive on the side remote from the tongue, the other side of said base portions and the side of the loop remote from the tongue being also provided with adhesive, the portions of the strip engaging the tongue being free from 45 adhesive, said slot being tapered from end to end with the outer end wider.

MATHIAS DIRSCHL.
